US0D1025613S

(12) **United States Design Patent** (10) **Patent No.:** **US D1,025,613 S**
(45) **Date of Patent:** **** May 7, 2024**

(54) **SCRUBBING DEVICE**

(71) Applicant: **Sud Scrub LLC**, San Gabriel, CA (US)

(72) Inventors: **Raymond Truong**, San Gabriel, CA (US); **Steven Truong**, San Gabriel, CA (US)

(73) Assignee: **SUD SCRUB LLC**, San Gabriel, CA (US)

(**) Term: **15 Years**

(21) Appl. No.: **29/925,716**

(22) Filed: **Jan. 25, 2024**

Related U.S. Application Data

(63) Continuation of application No. 29/913,278, filed on Sep. 28, 2023, which is a continuation of application No. 29/865,722, filed on Aug. 9, 2022, now Pat. No. Des. 1,010,961.

CLAIM

The ornamental design for a scrubbing device, as shown and described.

DESCRIPTION

FIG. 1 is a perspective view of a scrubbing device.

FIG. 2 is a left view thereof.

FIG. 3 is a right view thereof.

FIG. 4 is a front view thereof.

FIG. 5 is a rear view thereof.

FIG. 6 is a top view thereof; and,

FIG. 7 is a bottom view thereof.

The broken lines in the figures show portions of the scrubbing device that form no part of the claimed design.

1 Claim, 5 Drawing Sheets
